(57) **CLAIM**

The ornamental design for a swirl chamber, as shown and described.

DESCRIPTION

FIG. 1 is a perspective view of a first end of a swirl chamber according to our new design.

FIG. 2 is a perspective view of a second end, opposite the first end, of the swirl chamber.

FIG. 3 is a longitudinal view of the first end of the chamber. FIG. 4 is a longitudinal view of a second end of the swirl chamber.

FIG. 5 is a first side view of the swirl chamber.

FIG. 6 is a second side view, opposite the first side, of the swirl chamber.

FIG. 7 is a top view of the swirl chamber; and,

FIG. 8 is a bottom view, opposite the top thereof, of the swirl chamber.

The broken lines illustrate portions of the swirl chamber and form no part of the claimed design.
